UNITED STATES PATENT OFFICE.

GUSTAVUS A. SCHLECHTER, OF READING, PENNSYLVANIA, ASSIGNOR TO G. A. SCHLECHTER CO., OF READING, PENNSYLVANIA, A CORPORATION OF PENNSYLVANIA.

SCARF-PIN.

1,053,539.

Specification of Letters Patent.

Patented Feb. 18, 1913.

Application filed August 13, 1912. Serial No. 714,802.

To all whom it may concern:

Be it known that I, GUSTAVUS A. SCHLECHTER, citizen of the United States, residing at Reading, in the county of Berks 5 and State of Pennsylvania, have invented certain new and useful Improvements in Scarf-Pins, of which the following is a specification.

This invention relates to improvements in 10 scarf pins and the object in the present instance is to provide a device of this character with means for easily removing and replacing the stone or jewel from the mounting.

15 The invention consists of a pair of plates slidably arranged one on the other, and each of which is provided with a pair of jewel securing prongs, and the arrangement is such that stones of varied size and shape 20 may be secured in the mounting.

The invention is more fully described in 25 the following specification and clearly illustrated in the accompanying drawing, in which:—

Figure 1 is a front elevation of the 30 mounting with the stone removed, but its position being indicated by dotted lines. Fig. 2 is a side view of Fig. 1. Fig. 3 is a rear elevation of the mounting, with the pin and spring removed to more clearly show the parts.

The numeral 1 designates the rear plate 35 which is formed with an ear 2 at its upper end, to which ear a stick pin 3 is secured. This plate 1 is also formed with an aperture 4 near its upper end and with an open end slot 5 at its lower end.

The numeral 6 designates the front plate, 40 which rests on and is adapted to slide against the surface of the rear plate 1. This plate has an ear 7 pressed from its body at about the center, and this ear, when in position, passes through and travels in the opening 4 of the plate 1. The plate 6 is also 45 formed at its lower end with a rearwardly bent tongue 8 adapted to travel in the slot 5 and this tongue is formed with side projections 9 which tend to keep it in position against the rear plate. Each plate is provided with two prongs 10, the rear plate

having the prongs at the lower end and the front plate having them at the upper end; these prongs are adapted to secure and hold a suitable stone or jewel 11.

Interposed between the ears 2 and 7 is a 55 coiled spring 12 which surrounds the pin 3; this spring tends to draw the upper and lower prongs toward each other to firmly grasp the stone. It is evident that to place a stone in position, or to remove it after it 60 has been so placed, it is merely necessary to slide the plates so that the prongs will move away from each other, which movement will compress the spring, and the stone is placed in position. The release of the plates will 65 cause the spring to draw the prongs securely against the edge of the stone and securely hold it. It is also evident that with device, stones of varied size, as well as of varied contour may be engaged and that the 70 stones may be removed and replaced with ease.

Having thus fully described my invention, 75 what I claim and desire to secure by Letters Patent is:—

1. In a scarf pin the combination of a pair of plates slidably arranged on each other, each of which is formed with a rearwardly projecting ear, a pin secured to one of said ears and passing through the other, 80 and a coiled spring located between the ears and surrounding the pin, each of said plates having a pair of prongs, between which pairs of prongs a stone may be secured.

2. In a scarf pin, a rear plate formed 85 with a rearwardly projecting ear at its top, an opening near one end and an open end slot at the other end; a pin secured to said ear; a coiled spring seated against the ear and surrounding the pin; a front plate 90 formed with a tongue adapted to travel in said slot, an ear formed on said front plate and passing through said opening, said ear adapted to bear against one end of the spring; each of said plates having a pair of 95 prongs at its outer end between which pairs of prongs a stone may be engaged.

3. In a scarf pin a plate formed with an ear thereon and a pin secured to said ear; a second plate slidably arranged on the first 100

2
named plate and having an ear projecting through said first named plate through which last named ear the said pin passes; and a spring mounted on said pin between 5 the ears of the said plates, each plate having a pair of prongs between which pairs of prongs a stone may be removably engaged.

In testimony whereof I affix my signature in presence of two witnesses.

GUSTAVUS A. SCHLECHTER.
